MANUFACTURE OF LEAD TUBES AND CABLE SHEATHS

Georg Zapf, Cologne, Germany, assignor to
Felten & Guilleaume Carlswerk Aktiengesell-
schaft, Cologne-Mulheim, GermanyApplication April 20, 1934, Serial No. 721,631
In Germany March 31, 1933

1 Claim. (Cl. 207—4)

This invention relates to a form of press block for the manufacture of lead tubes, more particularly cable sheaths in presses having a vertical receiver or gate and a horizontal mandrel. It 5 has already been proposed to use in such presses a press block in which the lead is conveyed from the receiver to the annular chamber surrounding the mandrel through a narrow passage and two channels which are disposed on either side of the 10 annular chamber and are connected with one another by the narrow passage. Below the mandrel the two lead streams meet one another at an obtuse angle and form a seam in the lead sheath, for instance as shown in Fig. 1.

15 The lead oxides which form when the molten lead is being poured into the receiver and are deposited in or at the seam of the lead sheath during the pressing operation hinder the satisfactory welding of the latter. This fact which 20 is well known to those skilled in the art easily causes cracks to form in or close to the seam of the sheath.

In the manufacture of welded tubes it is known that the overlapped welded seam is superior as 25 regards its strength and tightness to the butt-welded joint. With this experience in view the invention has for its object to manufacture a pressed tube in which instead of the butt-welded joint shown in Fig. 1 an overlapped welded joint 30 according to Fig. 2 is formed. The lead oxides which in the press heads as hitherto used accumulate in the joint are distributed in the overlapped joint in such a manner that they no longer hinder the forming of a satisfactory joint. According 35 to the invention the overlapped joint can be produced by the channels of the annular chamber being caused to converge in such a manner below the mandrel that the lead streams flowing through them overlap one another as they enter 40 the annular chamber.

Figs. 3 to 5 show a constructional example of a press block according to the invention in three different sections, the press block being shown in Fig. 1 in horizontal section and in Figs. 4 and 45 5 in two vertical sections A—B and C—D. The

lines of flow indicated in the drawing represent the direction of flow of the lead in the different parts of the press head, the left hand and right hand half and the overlapping and overlapped part of the lead stream being shown differently.

In the drawing *a* is the receiver or gate with a cylindrical bore and *b* the press block. The bore of the receiver emerges at *c* into a narrow passage *d* of a kind known per se, which on all sides surrounds the mandrel *e* lying at right angles to it and opens at all sides into the annular chamber *f* surrounding the mandrel *e*. The ring *g* forms together with the mandrel *e* the outlet opening of the press block for the pressed tube. For enabling the lead in the annular chamber 70 to be guided below the mandrel in two streams overlapping one another, the cross-section of the narrow passage *d* is widened laterally and at the bottom to form channels *h* and *i*, the latter being so arranged that they lie one behind the other without a dividing wall below the mandrel and form a chamber *k* of about double the cross sectional area of one channel. The chamber *k* opens at the top into the narrow passage *d*. The cross-sectional dimensions of the lateral and bottom widening of the channel *d* depend on the condition that a uniform pressure drop and consequently a uniform supply of lead shall take place along all the paths of supply.

What I claim is:

For use in the manufacture of cable sheaths and other lead tubes in presses having a vertical receiver or gate and a horizontal mandrel, a press block, an annular chamber in the said press block surrounding the mandrel, two channels, one on either side of the annular chamber, and a narrow passage connecting the two channels for conveying the molten lead from the receiver to the annular chamber, the channels converging below the mandrel in overlapping manner so as to cause 90 the lead streams flowing through them to overlap one another where they enter the annular chamber.

GEORG ZAPF.
